UNITED STATES PATENT OFFICE.

OLAF HENRICHSEN, OF NEW YORK, N. Y.

RACE-COURSE MACHINE.

No. 815,165.

Specification of Letters Patent.

Patented March 13, 1906.

Application filed March 23, 1905. Serial No. 251,584.

To all whom it may concern:

Be it known that I, OLAF HENRICHSEN, a citizen of the United States, and a resident of the city of New York, borough of Brooklyn, in the county of Kings and State of New York, have invented a new and Improved Race-Course Machine, of which the following is a full, clear, and exact description.

My invention relates to toy race-courses of the kind used for testing strength or skill.

More particularly stated, my invention relates to a toy race-course in which dummies representing horses are caused to move at different speeds and over different distances, so as to simulate a race.

Reference is to be had to the accompanying drawings, forming a part of this specification, in which similar characters of reference indicate corresponding parts in all the figures.

Figure 1 is a plan view of one form of my race-course. Fig. 2 is a central vertical section through the same, showing the electric-motor mechanism and interior construction generally. Fig. 3 is a side elevation, partly in section, showing one of the blowpipes used for controlling the machine. Fig. 4 is a fragmentary sectional detail showing the mouthpiece of the blowpipe. Fig. 5 is a diagram of the wiring. Fig. 6 is a detail vertical section through one of the electric motors; and Fig. 7 is a vertical section, partly diagrammatic, showing another form of my invention in which a motor-car is propelled electrically, but controlled by means of a blowpipe.

A central platform 8 is encircled by and in registry with a number of rings 9, spaced apart by channels 10 and secured upon radial bridges 11. These bridges are provided with suspension-rods 12, which pass through the rings 9 and are secured at their lower ends by means of nuts 13. An outer platform 14, preferably of angular conformity, as shown, is connected rigidly with the bridges 11 and rests upon a casing 15, so as to close the top thereof. A number of dummies 16, representing horses, are mounted upon as many radial arms 17 18 19 20, these arms being rigidly connected with as many revoluble casings 20^a, whereby the arms and dummies are caused to rotate. Each casing 20^a rides upon a ball-bearing 21, carried by a common vertical stem 22, which extends from top to bottom of the casing and engages the central

platform 8. A sleeve 23, of insulating material, prevents electrical communication between the vertical stem 22 and the casing 20^a. Another sleeve 24, of insulating material, mounted within each casing 20^a, encircles the vertical stem 22. This sleeve 24 is provided with a stationary commutator 25. A ball-bearing 26 supports the cover 26^a of the casing 20^a. The commutator 25 is connected by wires 27 28 with armature-magnets 29 30. Field-magnets 32 33 are mounted within the casing 20^a and are therefore revoluble around the armature-magnets 29 30. Within the several casings 20^a are revoluble brushes 34 35 34^a 35^a 34^b 35^b 34^c 35^c, engaging a number of commutators 25 25^a 25^b 25^c, as indicated in Fig. 5, carried by conducting-arms 36 37, which are mounted upon the top of the casing and insulated therefrom by means of plates 38, of insulating material. These arms 36 37 are connected by brushes 39 40 with contact-rings 41 42, the ring 41 being rigid and in electrical communication with the stem 22, while the ring 42 is insulated from the stem by means of a sleeve 43, of dielectric material. This sleeve is provided with an aperture 44. The stem 22 is provided with apertures 45, and these apertures are used for threading wires therethrough. By means of a binding-screw 46 a wire 47 is connected with the stem 22.

Each of the motors is connected by a separate wire 48, 49, 50, and 51 with a corresponding rheostat 52, 53, 54, and 55, each rheostat being provided with the usual contact-buttons 56 and with the ordinary resistance-windings 56^a. (Shown diagrammatically in Fig. 5.) Each rheostat is further provided with a contact-arm 57, pivoted at 58 and free to successively engage the contact-buttons 56, so as to cut in or out a greater or lesser length of the wire in a manner well understood in relation to rheostats. A pitman 59 is connected with the contact-arm 57 by means of a pivot 60 and is also connected with a piston 61 by means of a pivot 62. A spring 64 tensions the piston 61; as indicated in Fig. 3, so as to normally leave the contact-arm 57 out of communication with the resistance-coils. Each rheostat is still further provided with a blowpipe 63, terminating in a mouthpiece 65, and within each mouthpiece is a rubber washer 66, provided with a central aperture 67.

The several players or other operators pro-

vide themselves with quills 68 and each player inserts his quill within one of the apertures 67. By blowing into the quills 68 the pressure of the breath causes the piston 61 to travel to a greater or lesser distance, compressing the spring 64 and causing the contact-arm 57 to travel angularly around, so as to successively engage and disengage the contact-buttons 56. In addition to the strength required for throwing the contact-arm 57 around to a considerable angle more or less skill may be required to keep the arm upon a button, and thus keep the circuit closed, for the reason that the spring 64 is active and with the least relaxation of the breath tends to move the arm 57 back toward its normal position.

Leading to the rheostat 52 is a wire 69, which is in communication with wires 70, 71, 20 and 72, leading to the respective rheostats 53, 54, and 55, as indicated by the diagram in Fig. 5. The battery is shown at 73.

The operation of my device is as follows: A number of players decide by lot or otherwise which of the blowpipes they will severally be entitled to use and take their seats accordingly. Each player inserts his quill 68 into the rubber washer 66 and applying his mouth to the quill blows into the blowpipe 30 63. The pressure of his breath pneumatically displaces the contact-arm 57, as above described, with the result that the circuit is completed through the particular rheostat controlled by his blowpipe and the normal resistance of that circuit is reduced to a greater or lesser extent, according to the degree of angular movement described by the contact-arm 57 under his control. For the rheostat 52 the circuit thus completed is as follows: 40 From the battery 73, wire 47, brushes 34 35, commutator 25 to the lowermost motor, wire 48, rheostat 52, and return-wire 69 back to the battery 73. The circuits for the other motors are similar. As some of the players 45 have greater strength than others for the purpose of displacing the piston 61 and also have greater skill in keeping the arm 57 constantly upon some one or the other of the contact-buttons, it follows that there may be 50 a considerable diversity in the relative distances traversed by the several dummies and in the speeds at which these dummies travel. In this way any number of games of skill can readily be played.

55 The provision that each player is provided with a separate quill 68 is based upon sanitary grounds, the idea being that this arrangement is less injurious to health, and as the quills cost practically nothing they may be thrown away after being once used.

In the form shown in Fig. 7 the rheostat 75 is provided with contact-buttons 76 and is of substantially the same construction as those above described. It therefore has the con-

tact-arm 57 and blowpipe 63, with mouth-piece 65. This rheostat 75 is provided with a binding-screw 77, from which a wire 78 leads to a battery 79. Connected with this battery and with the contact-arm 57 are wires 80 81, which are also connected with 70 the respective rails 83 82 of a miniature railway-track. Engaging the rail 82 is a wheel 84, driven by gearing 85, the latter being actuated by a revoluble armature-shaft 86, mounted upon the motor 87, the motor mechanism *per se* being old and well known. The motor 87 is in communication with the wheel 84 by means of a wire 88^a and by means of a wire 88 is in communication with the wheel 90. This wheel is provided with a bearing 89, which is insulated by means of a plate 91, of dielectric material. The car-body is shown at 92 and is carried by the wheels 84 90. This form of my apparatus is used as follows: A player inserts a quill as above described and blows his breath into the blowpipe 63. In doing so he causes the contact-arm 57 to swing angularly around, so as to cut out a greater or lesser resistance of the rheostat. In doing this he closes the circuit 90 and cuts out a greater or lesser resistance, thereby energizing the motor 87 and conferring upon the railway-carriage a degree of speed commensurate with the distance traversed by the arm 57. Contests may thus be 95 conducted, so that the apparatus affords an indefinite amount and variety of amusement.

Having thus described my invention, I claim as new and desire to secure by Letters Patent—

1. In an apparatus of the character described, the combination of a blowpipe, a cap fitting thereupon, a washer held in engagement with said blowpipe by said cap, a quill inserted through said washer and removable therefrom, and mechanism controllable by said blowpipe for simulating a race.

2. In an apparatus of the character described, the combination of a blowpipe, a rubber washer disposed adjacent to the end thereof, means for holding said rubber washer against said blowpipe, a tubular member inserted through said rubber washer and removable therefrom, and mechanism controllable by said blowpipe for simulating a race.

3. In an apparatus of the character described, the combination of a plurality of dummies, separate supporting-stems therefor, a plurality of electric motors connected, respectively, with said stems, and means controllable by the pressure of the human breath for causing said motors to move said stems at different speeds.

4. In an apparatus of the character described, the combination of a plurality of electric motors, each provided with a supporting-stem movable around a center, dummies mounted upon said supporting-stems

and adapted to simulate race-horses or the like, rheostatic mechanism connected with said motors for varying the speed of said dummies, and a blowpipe connected with said rheostatic mechanism for controlling the same.

5 In testimony whereof I have signed my

name to this specification in the presence of two subscribing witnesses.

OLAF HENRICHSEN.
